UNITED STATES PATENT OFFICE.

ROBERT PATRICK COSTELLO, OF CALGARY, ALBERTA, CANADA.

HOT-AIR FURNACE.

Application filed June 30, 1923. Serial No. 648,823.

To all whom it may concern:

Be it known that I, ROBERT PATRICK COSTELLO, a subject of the King of Great Britain, and resident of the city of Calgary, in the Province of Alberta and Dominion of Canada, have invented certain new and useful Improvements in Hot-Air Furnaces, of which the following is a specification.

This invention relates to improvements in hot air furnaces, and particularly to hot air self-feeding furnaces designed to burn the cheaper grades of coal.

The objects of the invention are to provide a self-feeding furnace of this description that can be most economically operated and that will burn coal of an inferior quality with equally satisfactory results to those attained by the more expensive grades of coal.

Further objects are to provide a furnace of this kind that will be smokeless and give a high degree of efficiency in combustion.

With these and other objects in view, the invention consists essentially in the combination with a suitable frame provided with an inclined grate and suitable baffles, of a swingingly mounted hopper means on the furnace for feeding coal thereto.

Referring now to the drawings, in which like characters of reference indicate corresponding parts in each figure:

Figure 1 is a front elevation of the furnace, partly in section, showing the interior.

Figure 2 is a vertical section view of the furnace through the grate and swinging hopper.

Figure 3 is a section on line 3-3 of Figure 2.

Figure 4 is a front elevation of the upper portion of the furnace showing the hopper.

In the drawings:

A designates the furnace as a whole so far as outward appearance and construction are concerned, being substantially similar to the ordinary hot air furnace. It, however, could advantageously be made of rectangular form instead of circular. The furnace has an outer casing 10 and an inner shell 11 formed, more or less, concentric with the outer casing, and forming a space for heated air therebetween.

The shell 11 supports a radiator drum 12 provided with the usual smoke duct 13 leading to a smoke pipe 14. A direct or indirect draught damper is provided in this drum 12 operated in the usual manner. The

fireplace 15 is enclosed at the rear and sides by the shell 11, and a combustion space 15^a leads to the radiator drum 12. An auxiliary air intake is provided at 16 to lead above the fuel. The ash pit door 17 gives access to the ash pan 18, which door also contains the main draught damper 19.

20 are a plurality of grate bars, suitably arranged on an inclined plane in such manner as to permit the feeding of coal downwards by gravity into the firepot 15, and communicating therewith is the hopper 22, placed outside the metal casing away from all heat and fitted to the front of the furnace at 23 by means of hinges or the like 22^a. The hopper is adapted to be swung sideways when necessary, so that when it is empty the fire pot can be easily cleaned out, and the fire grate freed from clinkers 75 with a minimum amount of trouble.

A further advantage in this swinging hopper is that it permits wood or large coal or otherwise to be easily directly fed to the combustion chamber 15^a.

25 A chute 21 leads from the hopper 22 to the fireplace 15 and is constructed entirely within the furnace. This chute comprises a lower plate 25 hinged to the casing 10 at 25^a and an upper plate 24 which is rigidly mounted on the side or wall plates 26 as shown in Figure 2 of the drawings. The lower plate 25 has its free end resting against the grate bars 20 and is hinged 80 so as to be raised out of the way when the grate is to be cleaned or removed.

25^a To the lower end of the plate 24^a is hinged a small plate 24^a hinged at 27. The sides 26 of the chute are formed by parts of the shell 11. A rod is connected to the hinged plate 24^a leading to a crank 27^a outside the furnace.

30 There is a pawl and ratchet 27^b on the body of the furnace so that, when the crank is turned and the plate 24^a is adjusted in the various positions, it will be held in the various positions desired. The object of having the upper part of the chute movable, or adjustable as by a plate 24^a, is to provide a restricted outlet for the chute so that various thicknesses of fuel are built up on the grate bars 20; for instance, if fine fuel is used, the chute will be blocked as much as possible so that there is utilized in the fire place only a thin layer of fuel. If large sized fuel is used, the chute may be opened 105 to its full extent, thereby giving a deep

body of fuel on the grate 20 and in the fire place 15. Various intermediate adjustments may be made.

28 is a cast iron baffle bolted to the two 5 sides of the furnace, and adapted to prevent heat from the combustion chamber 15^a coming into direct contact with the deadplate 24'. The coal chute 21 is also kept cool or 10 comparatively cool by means of an air inlet 29, adapted to permit cold air to enter the front of the furnace and to permit it to contact with the bottom and side of the chute and to flow into the combustion chamber by a passage 16, thereby assisting combustion 15 as well as providing an auxiliary air supply.

30 is a sliding ash plate at the bottom of the fire place, and is adapted to be pulled out by means of a hooked poker or rod. A 20 shut-off for the hopper may also be used.

From the foregoing, it will be seen that the essential features of my improved furnace are the inclined grate suitably mounted between side walls, adapted to receive coal 25 from a hopper swingingly mounted on the outside of the furnace, thereby providing ready access to the fire for purposes of poking ashes or clinkers downwards into the ash pit, after which the sliding ash plate 30 is pulled out by any suitable means, and the clinkers or otherwise removed. The hopper is then swung back into place and securely locked with a suitable locking device.

The joints between the hopper and the 35 furnace casing are preferably made airtight in any well-known manner. The feeding of the coal from the hopper is gradual and downwards as the fire burns, the swinging hopper also enables the fire to be kindled very easily. The swinging hopper, in 40 combination with the inclined grate, are, as will be noted from the foregoing, features of my invention.

As many changes could be made in the 45 above construction and many apparently widely different embodiments of my invention, within the scope of the claims, constructed without departing from the spirit or scope thereof, it is intended that all matter contained in the accompanying specification and drawings shall be interpreted as illustrative and not in a limiting sense.

What I claim as my invention is:

1. In a hot air furnace of the character 55 described, a furnace casing and, in combination, a hopper swingingly mounted on the outside of the casing and communicating therethrough, a feed door for the hopper, a fireplace provided with sloping grate 60 bars, wall plates for the fireplace adapted, in combination with suitable upper and lower plates, to form a chute between the hopper and the fireplace, an air intake for the combustion chamber, an adjustable 65 hinged plate in the chute, a slidably oper-

able ash plate for the fire place, and means for adjusting the hinged plate to regulate the supply of coal for the fireplace.

2. A furnace of the character described, 70 in combination with a fireplace having sloping grate bars, and a slideable ash plate, a feed hopper hingedly mounted on the outside of the furnace casing and communicating therethrough, a supply chute between the fireplace and the hopper, a hinged plate 75 adjustably mounted on the chute, means for raising and lowering the hinged plate to regulate the supply of fuel, a vertical baffle mounted adjacent the chute to deflect the heat therefrom, air intake means acting in combination with said baffle for cooling said chute.

3. In a device of the character described, 80 the combination with the furnace proper having a fireplace provided with a suitably arranged grate, of a swinging hopper on the furnace casing and communicating with the furnace therethrough, a fuel feed chute between the hopper and the fire place, a plate 85 operatively mounted on the chute, a lever for raising and lowering said plate, a vertical baffle deflecting heat from the chute, and air intake means adapted, in combination with said baffle for cooling said chute and completing combustion.

4. A hot air furnace of the character described having a casing, a substantially centrally located fireplace having an inclined 90 grate on one side thereof, an inclined coal chute inside the casing and at substantially the same inclination as the grate, a coal hopper on the outside of the casing leading into the chute, part of said chute being movable to restrict its outlet and lessen the thickness of coal on the grate in 95 the fireplace.

5. A hot air furnace as claimed in claim 4 having ash plates at the bottom of the grate.

6. A hot air furnace as claimed in claim 110 4, having the fireplace constructed with its ends and sides formed of the inner shell, an ash plate in the bottom of the grate, and a baffle plate in the combustion chamber to protect the chute from direct action of the 115 heated combustion.

7. A hot air furnace as claimed in claim 4, having the fire pot constructed with its ends and sides formed of the inner shell, an ash plate in the bottom of the grate, a baffle 120 plate in the combustion chamber to protect the chute from direct action of the heated combustion, a pivoted plate on the upper side of the chute, and means to adjust the plate to control the thickness of fuel on 125 the grate and in the fire pot.

8. A hot air furnace as claimed in claim 4, having the fire pot constructed with its ends and sides formed of the inner shell, an ash plate in the bottom of the grate, a 130

baffle plate in the combustion chamber to protect the chute from direct action of the heated combustion, a pivoted plate on the upper side of the chute, means to adjust 5 the plate to control the thickness of fuel on the grate and in the fire pot, an auxiliary draught damper with a duct leading around the chute and into the space above the upper dead plate of the chute to aid in cooling the coal fuel chute. 10 In witness whereof I have hereunto set my hand.

ROBERT PATRICK COSTELLO.
